UNITED STATES PATENT OFFICE.

WARREN S. BELDING, OF CHICAGO, ILLINOIS.

ARMATURE FOR DYNAMO-ELECTRIC MACHINERY.

SPECIFICATION forming part of Letters Patent No. 395,260, dated December 25, 1888.

Application filed March 22, 1888. Serial No. 268,066. (No model.)

To all whom it may concern:

Be it known that I, WARREN S. BELDING, a citizen of the United States, residing at Chicago, in the county of Cook and State of Illinois, have invented certain new and useful Improvements in Armatures for Electric Motors and Dynamos; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a hollow cast-iron core for armatures for electric motors and dynamos. I have ascertained that a greater efficiency may be attained by the use of a hollow core. By the use of such a core the generation of Foucault currents is reduced and the magnetic effect is concentrated in and near the surface of the core in close proximity to the field-magnets.

In the accompanying drawings, Figure 1 is a side elevation of one form in which my improved core may be made. Fig. 2 is a side elevation of one of the segments of the core shown in Fig. 1. Fig. 3 is a section through and in the direction of the axis of the armature.

An inspection of Fig. 3 will disclose the fact that the core is divided at right angles to its axis. The parts formed by this division are lettered A A. By thus dividing the core each part A is (unless divided transversely, as hereinafter set forth) a complete ring open all along one side, and may be cast in an ordinary sand mold.

In Fig. 2 one-half of one of the parts A is shown, the open side being directed toward the eye. Without making this division it would be a difficult matter to cast the core; but when the division is made any number of patterns for said parts may be put on a gate and cast in the common way.

The core may be said to be a ring-form shell divided or cut transversely to its axis to constitute two parts hollowed at their meeting sides. It may be uniform in thickness throughout its circumference to form a ring of the Gramme type, or it may have the polar

extensions A', which may or may not be hollow. The drawings show them hollow. When these said parts A A are placed against each other, the core is completed, and the coils B 55 may be wound upon it. When said coils have been applied, they hold the parts A A together. The ring may now be mounted upon a shaft in any suitable manner—as, for example, by means of two spiders, C C, having their arms 60 secured at the poles of the ring. Each of the parts A may also be divided radially into two or more parts, forming a segment of the ring. Fig. 2 shows such a segment, the division extending through diametrically-opposite poles, 65 and Fig. 3 shows this transverse division made in the same manner. When this transverse division is made, two segments of the parts A A may be brought together to complete a segment of the core and wound. The segment 70 of the entire core may thus be built up separately and afterward united end to end to complete the ring. It will be understood that these meeting ends may be united in several ways. In Fig. 1 the arms of the spiders C 75 are broad enough to extend over said ends, and two screws, C', pass through the arms, one into one and the other into the other end of the segments. The dotted lines indicate the line in which the ends of the segments meet. 80

The screws C' may pass from one spider-arm into the opposite one through the parts A A, thus securing said parts against movement upon each other. This may of course be accomplished in other ways. 85

Suitable insulation may be interposed between the parts A A.

I am aware that it is not new in the art to construct hollow iron armature-cores, and I do not claim, broadly, all forms of hollow cores. 90

I claim as my invention—

1. A hollow cast-iron armature-core composed of the annular parts A A, hollowed at their meeting sides, substantially as shown and described.

2. A hollow cast-iron armature-core composed of the annular parts A A, hollowed at their meeting sides, said parts being divided transversely into segments, substantially as shown and described.

3. The combination, with a hollow cast-iron armature-core composed of the annular parts

A A, hollowed at their meeting sides, of one or more spiders having arms attached to said core, substantially as shown and described.

4. The combination, with a hollow cast-iron armature-core composed of the annular parts A A, hollowed at their meeting sides, of two spiders, C C, applied to each side of said core and having their arms secured to the poles of said core, substantially as shown and described.

5. The combination of a hollow cast-iron armature-core composed of the annular parts A A, hollowed at their meeting sides, divided transversely into segments, of one or more spiders, C, the meeting ends of said segments being secured to the adjacent spider-arms, substantially as shown and described.

6. A hollow cast-iron armature-core composed of the annular parts A A, hollowed at their meeting sides and having the polar extensions A', substantially as shown and described.

7. A hollow cast-iron armature-core com-

posed of the annular parts A A, hollowed at their meeting sides and having the hollow 25 polar extensions A', substantially as shown and described.

8. A hollow cast-iron armature-core composed of the annular parts A A, hollowed at their meeting sides and having the polar extensions A', said parts A A being divided transversely into segments, substantially as and for the purposes herein set forth.

9. A hollow cast-iron armature-core composed of the annular parts A A, hollowed at 35 their meeting sides and having the polar extensions A', said parts A A being divided transversely through the middle of said polar extensions, substantially as shown and described.

In testimony whereof I affix my signature in presence of two witnesses.

WARREN S. BELDING.
